(57) **CLAIM**

The ornamental design for a bottle for a personal care product, as shown and described.

DESCRIPTION

FIG. 1 is a top/front perspective view of a design for a bottle for a personal care product;

FIG. 2 is a top/rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Any broken lines showing portions of the bottle for personal care product are for illustrative purposes only and form no part of the claimed design.

1 Claim, 6 Drawing Sheets
